DESIGN FOR A LOUD-SPEAKER OR THE LIKE

Carl C. Langevin, San Mateo, Calif.

Application May 27, 1943, Serial No. 110,313

Term of patent 14 years

To all whom it may concern:

Be it known that I, Carl C. Langevin, a citizen of the United States, residing at San Mateo, in the county of San Mateo and State of California, have invented a new, original, and ornamental Design for a Loud-Speaker or the like, of which the following is a specification, reference being had to the accompanying drawing, forming part thereof.

Fig. 1 is a perspective view of a loud-speaker showing my new design,

Fig. 2 is a side elevational view thereof, and Fig. 3 is a vertical mid-sectional detail showing particularly the bevelled flange section of the bell-shaped housing forming the upper part of the design.

I claim:
The ornamental design for a loud-speaker or the like, substantially as shown.

CARL C. LANGEVIN.
